SIGNAL LIGHT FOR AN AUTOMOBILE

Richard Laupot, New York, N.Y. (½ Retract-A-Belt Corp., 75 Clymer St., Brooklyn, N.Y. 11211)

Filed Feb. 18, 1966, Ser. No. 1,110

Term of patent 14 years

(Cl. D48—32)

FIG. 1

FIG. 2

FIG. 3

FIG. 4

FIG. 1 is a front elevational view of a figurine with automobile signal lights, showing my new design;

FIG. 2 is a rear elevational view thereof;

FIG. 3 is a side elevational view thereof; and

FIG. 4 is a top plan view thereof.

I claim:

The ornamental design for a signal light for an automobile, as shown.
